(57) **CLAIM**

The ornamental design for a baseball cap shaped frame for license plates, as shown and described.

DESCRIPTION

FIG. 1 is a front perspective view of a baseball cap shaped frame for license plates and pictures according to the present invention, showing the frame attached to a vehicle and holding a license plate.

FIG. 2 is another front perspective view thereof.

FIG. 3 is another front perspective view thereof.

FIG. 4 is a front elevation view thereof.

FIG. 5 is a rear elevation view thereof.

FIG. 6 is a right side elevation view thereof, the left side elevation view being a mirror image of the right sided elevation view.

FIG. 7 is a bottom plan view thereof; and,

FIG. 8 is a top plan view thereof.

The broken lines showing a vehicle and indicia are for the purpose of illustrating environmental structure and form no part of the claimed design.
